(57) **CLAIM**

The ornamental design for a digital X-ray detector, as shown and described.

DESCRIPTION

FIG. 1 is a front perspective view of a digital X-ray detector showing our new design;

FIG. 2 is a top view of the front perspective view shown in FIG. 1;

FIG. 3 is a back perspective view thereof;

FIG. 4 is a top view of the back perspective view shown in FIG. 3;

FIG. 5 is a left-side view of the front perspective view shown in FIG. 1;

FIG. 6 is a right-side view of the front perspective view shown in FIG. 1;

FIG. 7 is a front view thereof; and,

FIG. 8 is a back view thereof.
